BUSHING TERMINAL

Application filed January 18, 1929. Serial No. 333,468.

Our invention relates to bushing terminals and particularly to terminals for the outer ends of high-voltage bushings.

One object of our invention is to provide a bushing of the above-indicated character that shall be readily employed interchangeably in applications requiring, or desirably utilizing, through conductors of different kinds.

10 Another object of our invention is to compensate for discrepancies sometimes occurring between the relative lengths of bushings and through conductors therefor.

Another object of our invention is to provide a bushing which may be removed from service position for repair or replacement without detaching the through conductor thereof at its inner end and which shall facilitate the introduction of the through conductor to a bushing when the latter is being placed in position.

Another object of our invention is to provide a bushing that shall prevent breathing and the entrance of oil or other fluid insulating medium into the bushing from a receptacle with which it cooperates.

Another object of our invention is to facilitate the assembly and repair of the bushing and its associated apparatus.

30 A further object of our invention is to provide a bushing structure that shall be simple and durable in construction, economical to manufacture and effective in its operation.

In certain bushing practice, especially 35 that wherein relatively high voltages are employed, and wherein relatively long tubular refractory or porcelain elements are employed, the refractory elements sometimes vary in length as much as six percent. This 40 variation is caused by shrinkage effects in the ceramic material during firing, as is well known.

By reason of the fact that the refractory elements have definite shapes at the ends thereof for the reception of terminal members, they cannot be cut off to render them of uniform lengths and, consequently, other means must be employed to compensate for the differences.

50 Also, in bushings having through open-

ings which communicate with the interiors of tanks or casings of electrical apparatus, there is sometimes a breathing or other effect, caused by heating and the expulsion forces of opening a circuit, which causes the 55 oil or other fluid medium in the tank to pass through the bushing. This effect is objectionable.

Further, there are services of different kinds where substantially similar bushings 60 may be employed, such as in connection with circuit breakers and transformers, in which terminals and conducting leads of slightly different character are desirable.

It is our aim to overcome the above-mentioned objections by compensating for the different relative lengths of the connectors and the bushings, through which the conductors are to extend, to prevent the above-mentioned breathing, to permit a bushing to be readily 70 adapted, with only slight change, for operation in connection with different apparatus and to otherwise desirably improve the structure.

Accordingly, in practicing our invention, 75 we provide a bushing embodying a tubular refractory element, a tubular through conductor, a sealing cap for the tubular through conductor and a combined terminal and adjusting means for a flexible through conductor to accomplish the purposes of our invention.

Figure 1 of the accompanying drawings is 80 a side elevational view of a bushing constructed in accordance with our invention;

Fig. 2 is an enlarged view, taken along the line II—II of Fig. 3, and

Fig. 3 is an enlarged longitudinal sectional view of the upper end of the structure shown in Fig. 1.

The device comprises, in general, a condenser-bushing element 2, means 3 at an intermediate portion thereof for securing the same to a tank or casing with which the bushing is to cooperate, a tubular refractory weather-protective member 4, an upper terminal structure 5 and a lower end member 6.

The bushing structure 2 is of a usual well-known condenser type comprising a plurality of di-electric layers 8 between which are dis-

posed conducting layers (not shown) of material such as tin, lead or aluminum foil. In this structure, which is disposed about a central tubular conductor 9, as shown in Fig. 3, the conducting and di-electric layers are of successively outwardly greater diameters and shorter lengths to provide nearly equal capacity between the condenser elements.

The outer or weather-exposed portion of 10 the bushing element 2 is protected by the refractory or porcelain member 4 which is preferably constructed in one piece and provided with a plurality of surface-creepage flanges or petticoats 12. The member 4 is secured 15 to the structure 3 in any suitable manner, not germane to this invention, whereby the bushing is held in position in an opening in a tank cover (not shown).

The upper terminal structure 5, as shown 20 more clearly in Figs. 2 and 3, comprises a ring 14, of substantially L-shape in cross-section, having one arm or flange secured to the outer end of the member 4, as by a body of cement, alloy or other suitable medium 15. 25 The other arm of the element 14 is provided with openings for the reception of screws 16 which extend into a weather casing element 18. A sealing gasket 19 is clamped in position by the screws 16 between the members 4 30 and 18.

The weather casing 18 further comprises an inner flange 21, a plurality of tapped openings 22 and portions 23 for the reception of lifting eyes 24. A thrust nut 25 is 35 mounted on the tubular conductor 9 and so cooperates with the flange 21 that, when the bushing is lifted by means of the eyes 24, the weight of the bushing is placed on the tube 9 and not on the sealing medium 15.

40 A terminal element at the upper end of the tubular conductor 9 comprises a screw-threaded sleeve portion 27 and a box or receptacle-like portion 28 having an inner opening 29 and a terminal-receiving portion 45 30. A cover 32 is secured to the portion 28 by screws 34 which compress a sealing gasket 35 between the members 28 and 32.

An outer cap member 37 is provided with 50 peripheral openings for the reception of screws 39 which secure the same to the weather casing 18. The cap 37 is also provided with a screw threaded outer terminal stud 40 and a tapped opening 41 adjacent thereto. A conductor 42 is connected between the 55 cap member 37 and the portion 28 by screws 44 and 45, respectively.

The structure, as described so far, may be 60 employed as a bushing for a circuit interrupter wherein a stationary contact terminal (not shown) is employed as a substitute for, or as an addition to, the lower member 6, as indicated in Fig. 1. In this case, the tube 9 constitutes the through conductor.

65 However, when the bushing is to be employed in connection with a transformer or

other apparatus having terminals remotely disposed with respect to the lower member 6, it is desirable to employ a flexible conductor 46, as indicated in Figs. 1 and 3, extending through the tubular conductor 9.

In the latter application, it is desirable to have the flexible conductors 46, of similar bushings, of the same length and to provide them with ends, such as an end 48 shown in Fig. 3, which cooperate with, and are secured to, terminal portions similar to the terminal portion 40, as by screws 50, the lower ends being extended directly to the transformer coils or other apparatus of which they may 70 constitute permanent parts.

Since, as hereinbefore stated, the refractory member 4 varies considerably in length in different bushings, the flexible conductor 46, to be of a fixed length, must be of sufficient length to extend from its inner end (not shown) to the terminal portion 40 in the longest bushing. Hence, when it is employed with a bushing employing a shorter member 4, the conductor 46 is longer than necessary and will be in a slack condition 80 unless compensated for, as by our invention.

To eliminate this slack, the flexible conductor 46 is drawn taut through the tubular conductor 9 and through the opening 29 and clamped in taut condition by a cam clamping member 52 that is pivotally mounted on a portion 53 of the portion 28 and held in position by a nut-and-bolt device 54.

90 In the above described structure, when employed, as a transformer bushing, the flexible conductor 46 may be readily fished up through the tubular conductor 9 and secured in position, as illustrated in Fig. 3. The elements 28 and 32, together with the sealing gasket 35, constitute a hermetically-tight 100 sealing means to prevent breathing and the passage of oil into or through the tubular conductor 9. When it is desired to utilize the bushing as a circuit-interrupter terminal, the flexible lead 46 may be omitted and the tube 9 still be hermetically sealed, as above 105 described.

110 While we have shown and described a particular form of our invention, changes may be effected therein without departing from the spirit and scope thereof, as set forth in the appended claims.

115 We claim as our invention:

1. In combination, a bushing, a tubular conductor extending therethrough, a flexible conductor extending through said tubular conductor and means on said tubular conductor for eliminating slack in said flexible conductor.

120 2. In combination, a bushing, a tubular conductor therein, a cap for the tubular conductor comprising a terminal member on the conductor and a cover member for the terminal member, a flexible conductor in the tubular conductor secured to said terminal

member, and a terminal cap for the bushing electrically connected to said terminal member.

3. In combination, a tubular bushing element, a tubular conducting element extending therethrough, a flexible conductor extending through said tubular conductor, and an end-closure member for one of said elements, including means for holding said flexible conductor after slack has been taken up therein.

4. In combination, a bushing, a terminal, a flexible conductor having a portion in the bushing and an end secured to said terminal, and means for tensioning the conductor including means for holding a buckled portion of the conductor between the holding means and said terminal.

5. In combination, a bushing, a flexible conductor having a portion therein, and means supported by the bushing and adjustable laterally to the conductor for holding a portion of the conductor in buckled form to eliminate slack in the conductor.

25 6. In combination, a bushing, a flexible conductor having a portion therein, and cam-clamping means acting laterally to the conductor for holding the conductor after slack has been taken up therein.

30 7. In combination, a bushing, a flexible conductor having a portion therein, an end-closure element for the bushing, and means associated with said element and adjustable laterally to the conductor for holding the conductor after slack has been taken up therein.

40 8. In combination, a bushing, a flexible conductor having a portion therein, said conductor having an end terminal portion, a co-operating terminal portion carried by the bushing, and means for holding another portion of the conductor in buckled form to eliminate slack in the conductor.

45 9. In combination, a bushing, a flexible conductor having a portion therein, said conductor having an end terminal portion, a co-operating terminal portion carried by the bushing, and means also carried by the bushing adjacent to said co-operating terminal portion for holding another portion of the conductor in buckled form to eliminate slack in the conductor.

50 10. In combination, a bushing, a flexible conductor having a portion therein, a tubular conductor surrounding the flexible conductor in the bushing, and means on the tubular conductor for holding the flexible conductor after slack has been taken up therein.

60 11. In combination, a bushing, a flexible conductor having a portion therein, a tubular conductor surrounding the flexible conductor in the bushing, end-closure means for the tubular conductor, and means associated with said end-closure means for holding the conductor after slack has been taken up therein.

12. In combination, a bushing, a flexible conductor having a portion therein, an end-closure cap for the bushing, a tubular conductor surrounding the flexible conductor in the bushing, an end-closure cap for the tubular conductor, means for conductively connecting said caps, terminal means in the tubular-conductor cap for the flexible conductor, and means in the tubular-conductor cap for holding the flexible conductor after slack has been taken up therein.

70 13. In combination, a conductor, a bushing surrounding the same and secured thereto, an end structure for the bushing including means whereby the bushing may be lifted, means for securing said end structure to the bushing, and means co-operating between the end structure and the conductor for transmitting the lifting forces to the conductor and thereby relieving said securing means of said forces.

80 14. In combination, a conductor, a bushing surrounding the same and secured thereto, an end structure for the bushing including means whereby the bushing may be lifted and having an inner shoulder, means for securing said end structure to the bushing, and a thrust nut on the conductor co-operating with said shoulder for transmitting the lifting forces from the end structure to the conductor and thereby relieving the securing means of said forces.

90 15. In combination, in a bushing, a dielectric tube, a metal tube secured in position therein and having a screw-threaded portion projecting from one end thereof, a metal collar surrounding, and secured to, said end of the dielectric tube, an element surrounding said projecting portion over the transverse surface of said end, sealing means between said end and said element, means for securing said element to said collar to impress said sealing means, said element having an annular inner shoulder surrounding said projecting portion, a thrust nut on said screw-threaded portion bearing against said shoulder, and means on said element whereby the bushing may be lifted.

100 In testimony whereof, we have hereunto subscribed our names this 8th day of January, 1929.
